PAPER DISPENSER

Frank L. Broeren, Menasha, Wis., assignor to
 Marathon Paper Mills Company, Rothschild,
 Wis., a corporation of Wisconsin

Application April 15, 1935, Serial No. 16,349

2 Claims. (Cl. 312—62)

This specification is in part a continuation of application Serial No. 736,155, filed July 20, 1934.

The object of this invention is to provide an improved and simplified form of device for dispensing interfolded paper sheets, particularly waxed paper sheets.

In particular the invention relates to the construction and mounting for the follower plate so disposed as to cause the plate, in traveling from the rear toward the front of the dispenser during the depletion of the stack, to maintain substantially uniform contact with the rear of the stack resting upon an inclined floor and without material slippage or displacement due to the swing of the follower plate which is carried upon the free end of a link pivoted below the floor level.

This and other objects, as will hereinafter appear, are accomplished by this invention, which is fully described in the following specification and shown in the accompanying drawing, wherein,—

Figure 1 is a perspective view of a dispenser embodying this invention;

Fig. 2 is an enlarged vertical section on the line 2 of Fig. 1;

Fig. 3 is a somewhat reduced partial vertical section on the broken line 3—3 of Fig. 2; and

Fig. 4 is a side elevation showing the edges of the interfolded sheets in expanded form.

The embodiment illustrated comprises a metal box or cabinet 10 having a cover 11 hingedly secured thereto at 12. The front of the cabinet is provided with a transverse slot 13 through which the sheets A are adapted to be pulled in a well known manner which will later be described. Behind this front are located bearing plates 14 and 15 which provide a throat converging toward the slot 13 and afford a limited surface contact for the foremost sheet of the stack, which is bowed forward in the center toward the slot by the pressure of the follower plate presently to be described.

The sheets, in stack formation, rest upon a floor 16 which is preferably inclined downwardly toward the front, and the sheets are pressed forwardly by means of a follower plate 17 which is pivotally connected at 18 to the upper end of a link 19, the lower end of the link being pivotally connected to a pin 20 which is carried by a member 21 secured to the bottom of the cabinet near the rear wall thereof. The link 19 is movable back and forth through a slot 22 in the floor 16 and is normally urged toward the front of the cabinet by means of a coiled spring 23 passing around the pin, as clearly shown in Fig. 3.

Thus the group of sheets of waxed paper or the like, which are previously interfolded as shown

in Fig. 4, are placed in front of the follower plate 17, the edge of the foremost sheet being passed through the horizontal slot 13. Thus as the user pulls on the front sheet A, shown in full lines, it becomes withdrawn through the slot, at the same time pulling through this same slot the forward edge of the next interfolded sheet, which then assumes the dotted line position.

The length of the link 19 and the location of its axis are so computed with relation to the inclination of the floor 16 down which the sheets travel in the depletion of the stack that the chord of the arc of movement of the free end of the link will lie substantially in parallelism with the oblique plane of the floor, so that as the follower plate advances it will not be materially displaced from its area of contact against the medial region of the stack, with the result that there will be but slight slippage due to the fact that the stack travels forward upon an oblique surface while the follower plate travels through the arc of movement of the link upon which the follower plate is supported.

To facilitate the operation of drawing the first sheet through the slot 13, the end of the slot is cut out at the side 13a so as to permit the operator to insert his finger or a pointed instrument under the foremost sheet of paper, thereby enabling him to draw it through the front slot. A slot 13b is provided at one or both ends of the cabinet, through which the operator may observe when the supply of paper sheets needs replenishing.

While the device is adapted for the dispensing of paper sheets generally, it is particularly well adapted for dispensing waxed sheets which tend to slide on one another, the arrangement being one that prevents displacement of the sheets in the stack and permits withdrawal of the outermost sheet without disarranging the remaining sheets.

I claim:

1. A dispenser for sheets of paper comprising a container having a front panel provided with a transversely extending slot positioned intermediate the upper and lower edges of said sheets held adjacent thereto through which the sheets may be withdrawn singly, a forwardly and downwardly inclined floor having its rear portion elevated above the level of the bottom of the container for supporting the lower edges of sheets composing a stack, said floor being provided in its rear portion with a slot, a link extending through the slot in the floor and having its lower end pivoted between the floor and the bottom of

the dispenser, a follower plate pivoted to the upper free end of the link, and a spring acting against the link for urging the follower plate forward so as to hold said sheets in compressed condition adjacent said transverse slot.

- 5 2. A dispenser for sheets of paper comprising a container having in its front wall a transversely extending discharge slot positioned intermediate the upper and lower edges of said sheets
10 held adjacent thereto through which sheets may be withdrawn singly, a forwardly and downwardly inclined floor for supporting a stack of sheets

and feeding them standing vertically toward the discharge slot, said floor being provided in its rear portion with a slot, a link extending through said last named slot and pivoted below the floor, a follower plate pivoted to the upper free end of the link, and means for urging the follower plate forward so as to hold said sheets in compressed condition adjacent said transverse slot, the inclination of the floor and the chord of the arc of movement of the free end of the link being approximately parallel. 5 10

FRANK L. BROEREN.
